CLAIM

The ornamental design for a wrench, as shown and described.

DESCRIPTION

To the fullest extent permitted by law, the present design patent application claims priority to and the full benefit of nonprovisional patent application entitled "Wrench", filed on Nov. 12, 2002, having U.S. Ser. No. 10/293,839.

The present invention relates generally to wrenches, and, more specifically, to a wrench for aircraft engine repair.

FIG. 1 is a front perspective view of the wrench of the present invention.

FIG. 2 is a front view of the wrench of the present invention.

FIG. 3 is a rear view of the wrench of the present invention.

FIG. 4 is a top view of the wrench of the present invention.

FIG. 5 is a side view of the wrench of the present invention.

FIG. 6 is a bottom view of the wrench of the present invention; and,

FIG. 7 is a side of the wrench of the present invention.
